LAMP BEZEL FOR AUTOMOBILES OR THE LIKE

George W. Walker, Bloomfield Hills, Mich., assignor to Ford Motor Company, Dearborn, Mich., a corporation of Delaware

Filed Oct. 3, 1960, Ser. No. 62,351

Term of patent 7 years

(Cl. D48—32)

Fig. 1 is a front elevational view of a lamp bezel for automobiles or the like, showing my new design;

Fig. 2 is a side elevational view;

Fig. 3 is an enlarged partial section taken on the line 3—3 of Fig. 1;

Fig. 4 is a rear elevational view;

Fig. 5 is a sectional view taken on the plane indicated by the line 5—5 of Fig. 1; and

Fig. 6 is an enlarged partial section taken on the line 6—6 of Fig. 5.

I claim:

The ornamental design for a lamp bezel for automobiles or the like, as shown.
